(57) **CLAIM**

The ornamental design for a tube and cap spacer, as shown and described.

DESCRIPTION

FIG. 1 is a left perspective view of a tube and cap spacer in accordance with the present design;

FIG. 2 is a top view thereof;

FIG. 3 is a left side view thereof;

FIG. 4 is a rear view thereof;

FIG. 5 is a front view thereof;

FIG. 6 is a right side view thereof;

FIG. 7 is a bottom view thereof;

FIG. 8 is a right perspective view thereof;

FIG. 9 is a front view thereof showing the tube and cap spacer assembled with a tube and cap; and,

FIG. 10 is a front exploded view thereof showing the tube and cap spacer with a tube and cap.

The broken lines in the drawings depict environmental subject matter and form no part of the claimed design.

1 Claim, 10 Drawing Sheets
